ANSON SEARLS, OF NEW YORK, N. Y.

Letters Patent No. 74,484, dated February 11, 1868.

IMPROVEMENT IN PIVOTED STUMP-JOINT.

The Schedule referred to in these Letters Patent and making part of the same.

TO WHOM THESE PRESENTS SHALL COME:

Be it known that I, ANSON SEARLS, of the city of New York, have made a new and useful Improvement in Making Stump-Joints for carriage-top joints, which I call the "Pivoted Stump-Joint," of which the following specifications and accompanying drawings are an exact and clear description.

Pivoted Stump-Joints.

The nature of my invention consists in an improvement in the manner of making the centre-joint in carriage-prop joints with a pivot, entirely dispensing with the old style rivet, except for ornament, and also reducing the cost and increasing the strength and durability of the same. To better describe my invention, reference is made to the accompanying drawings, of which—

The journal or pivot C on the part A fits into the socket or pivot-hole D in the part B. The pivot C is riveted at or near the point e, thereby holding the joint firmly together for all purposes. For the purpose of attaching an ornament to the joint, a hole may be drilled through the pivot, marked red, O, fig. 1, and a rivet inserted, as shown by red lines in fig. 2. The corner left in at i is to increase the width of the joint and strength of the parts.

This invention is intended as an improvement on the "centre-joint" of A. SEARLS's adjustable prop-joint, patented November 5, 1867, and is designed to be used in connection with that joint, or separated, as a stump joint.

Having thus described my invention, for which I desire Letters Patent—

I claim an improved stump-joint, substantially as described, and for the purposes set forth.

Signed this, the second day of December, 1867.

ANSON SEARLS.
